UNITED STATES PATENT OFFICE.

CHARLES MACKENZIE ABERCROMBIE, OF BRIDGEPORT, CONNECTICUT,
ASSIGNOR TO WHEELER & WILSON MANUFACTURING COMPANY,
OF BRIDGEPORT, CONNECTICUT, A CORPORATION OF CONNECTICUT.

PRESSER-FOOT FOR HEMSTITCH SEWING-MACHINES.

SPECIFICATION forming part of Letters Patent No. 776,821, dated December 6, 1904.

Application filed October 31, 1901. Serial No. 80,684. (No model.)

To all whom it may concern:

Be it known that I, CHARLES MACKENZIE ABERCROMBIE, a citizen of the United States, residing at Bridgeport, in the county of Fairfield and State of Connecticut, have invented a certain new and useful Improvement in Presser-Feet for Hemstitch Sewing-Machines, of which the following is a full, clear, and exact description.

10 The object of this invention is to provide an attachment for sewing-machines for controlling hem-folds, as in the hemstitching of handkerchiefs or in the stitching down of hem-folds, as in the hemming of sheets, pillow-cases, &c., and in the seaming of hem-folds or materials wherein it is essential that the feed of the material to the needle shall be uniform, so as to prevent the fold from overlapping the finished end of the seam, which 15 occurs in the employment of the ordinary cloth-pressers.

The invention consists of a compound or duplex presser-foot the members of which are capable of independently yielding to the 20 work and are also capable of adjustment relatively to one another, all as I will proceed now more particularly to set forth and finally claim.

The particular class of work for which my 25 improved device is especially adapted is hemstitching, wherein several thicknesses or folds of material are passed beneath the feet at the same time, and I have accordingly illustrated my invention in connection with a hemstitch sewing-machine; but I do not wish to be limited in this respect, since such cloth-pressers are equally adapted to many other sewing-machines wherein the different thicknesses of material are simultaneously passed beneath 30 the presser-feet and require that the latter assume positions in different horizontal planes.

In the accompanying drawings, illustrating my invention, in the several figures of which like parts are similarly designated, Figure 1 35 is a front elevation of a hemstitch sewing-machine equipped with my improved cloth-presser, the face-plate being removed. Fig.

2 is a front elevation of my improved cloth-presser attached to a presser-bar. Fig. 3 is a side elevation of the cloth-presser looking 50 in a direction opposite to that in which the cloth-presser is viewed in Fig. 1. Fig. 4 is a rear elevation of the cloth-presser and bar. Fig. 5 is a perspective view of the cloth-presser and presser-bar. Fig. 6 is a perspective view of the presser detached from the presser-bar.

1 is the usual overhanging arm of the sewing-machine, mounted upon the bed-plate.

3 is the presser-bar, operatively mounted in 60 the end of the overhanging arm and having the usual presser-spring 4, interposed between the lifting-collar 5 and pressure-adjusting sleeve 6.

To the lower end of the presser-bar 3 are adjustably secured the respective legs 7 and 8 and in such manner that one of said legs will be capable of limited vertical movements relatively to the vertical movements of its co-acting leg. The leg 7 is supplied with a collar 9, having a set-screw 10 tapped therein, by means of which said leg is secured rigidly to the presser-bar. The leg 8 is supplied with two collars or short sleeves 11 and 12, fitted loosely on the presser-bar and adapted to receive the collar 9 between them. The distance between the two collars or sleeves 11 and 12 is somewhat greater than the thickness of the collar 9, so as to permit of vertical adjustments of the leg 8 upon the presser-bar 3.

13 is a collar secured upon the presser-bar 3 above the collar 11 by a set-screw 14, and interposed between the collars 11 and 13 is an auxiliary presser-spring 15, which exerts a 85 tendency to thrust the leg 8 downward.

16 is an adjusting-screw tapped in the collar 11 and adapted to bear upon the collar 9, so that by the adjustment of said screw limited vertical movements of the leg 8 with respect 90 to the leg 7 may be obtained, as will be clear by reference to Figs. 3 and 4. The collar 11 rearwardly from the threaded hole for the adjusting-screw 16 is split, as shown at 17,

and the two sections thus formed are drawn together by a screw 18, thus forming a pinch-joint whereby the adjusting-screw 16 is secured against unintentional adjustment.

5 In order to prevent the leg 8 from turning axially on the presser-bar and getting out of proper alinement with the leg 7, the body portion of said leg 8 is provided with angular portions 19 and 20, which angular portions 10 coact with corresponding angular portions 21 and 22, formed in the leg 7, and this construction while preventing axial movements permits vertical movements of the leg 8 relatively to the leg 7.

15 The presser-bar is restrained against turning by the presser-lifter collar 5 in the usual manner.

23 and 24 are presser-feet pivoted at the bottoms of the respective legs 7 and 8 in the 20 usual manner.

The leg 8 is made somewhat longer than the leg 7, as is clearly shown in Figs. 2 and 4, and by adjusting the screw 16 the distance which the foot 24 depends beneath the foot 25 23 may be regulated to meet the requirements of different thicknesses and texture, a great desideratum in this class of work.

When the presser-bar is lowered to bring the presser-feet upon the material, the foot 30 24 will first contact with the material, thus compressing the spring 15 by the more powerful action of the spring 4 until the foot 23 rests firmly upon the material. The pressure with which the foot 23 bears upon the material may be regulated by adjusting the collar 13 to put more or less tension upon the spring 15 independent of the pressure exerted by the spring 4.

As will be seen by reference to Fig. 6, the 40 presser-foot 23 is recessed at 25 to accommodate the action of the needle.

What I claim is—

1. The combination with a presser-bar, of two presser-feet independently and adjustably secured to said presser-bar, a spring on 45 said bar whereby said presser-feet have vertical movements in common, and a second spring adjustably secured upon said presser-bar for independently controlling the action of one of the presser-feet relatively to the 50 thickness of the material being sewed.

2. A sewing-machine presser-foot, comprising a spring-pressed leg and a foot thereon, said leg having a collar and means for adjusting it upon a support, another leg likewise having a foot, and provided with parallel collars, and means for securing said leg to said support with the collar of the first-named leg interposed between the collars of the last-named leg, substantially as described. 60

3. A sewing-machine presser-foot, of compound or duplex formation, comprising two legs, one of said legs having parallel collars, and means to secure the same upon a presser-bar, and the other leg having a collar adapted 65 to engage the presser-bar between the collars of the first-named leg and having a capability of adjustment between said collars and upon said presser-bar, a spring mounted upon the presser-bar above the uppermost collar, a 70 stop-collar upon the presser-bar, means to adjust said stop-collar to vary the tension of the said spring, and a set-screw in the uppermost collar for limiting the vertical movements of the leg having the parallel collars, 75 combined with a presser-bar.

In testimony whereof I have hereunto set my hand this 30th day of October, A. D. 1901.

CHARLES MACKENZIE ABERCROMBIE.
